UNITED STATES PATENT OFFICE.

FREDERICK JOHN SHAINSEY, SR., OF DAYTON, OHIO, ASSIGNOR TO KRENTLER-ARNOLD HINGE LAST COMPANY, OF DETROIT, MICHIGAN, A CORPORATION OF WEST VIRGINIA.

LAST.

No. 857,117.

Specification of Letters Patent.

Patented June 18, 1907.

Application filed November 1, 1904. Serial No. 230,903.

To all whom it may concern:

Be it known that I, FREDERICK JOHN SHAINSEY, Sr., a citizen of the United States, and a resident of Dayton, in the county of Montgomery and State of Ohio, have invented an Improvement in Lasts, of which the following description, in connection with the accompanying drawings, is a specification, like letters on the drawings representing like parts.

My invention relates to improving the heelpart of a hinged last in strength, external surface, or shape, and general serviceableness.

One of the most serious difficulties met with in the practical manufacture and use of multi-part lasts, especially hinged lasts, resides in the weakening of the heelpart which necessarily results from the numerous saw cuts, holes and rivets to which the heelpart is subjected in order to accommodate it to the devices which are necessary for its construction. For example, the front end thereof is cut obliquely down to the swinging point of the last and is thence severed along the line of the sliding faces of the forepart and heelpart, a vertical longitudinal saw kerf extends into the front end of the heelpart for the reception of the hinge, one or more rivets extend through the forepart transversely of the saw kerf, for holding the hinge, a vertical spindle hole is provided at the rear of said kerf for the jack-pin, and one or more holes and rivets extend transversely through the heelpart adjacent the thimble for binding the wood of the heelpart together. All this honeycombing of the heelpart tends to destroy its integrity and to weaken it; and when it is remembered that the heelpart of a last is, at best, small, narrow, short and frail, the reason is apparent for the extreme difficulty to which we have alluded. However, as the heelpart is obliged to withstand enormous pressures in the heeling operation, leveling, etc., which tend to crush it vertically, burst it laterally, and split it longitudinally, the said heelpart must be made strong; and hence various expedients have been resorted to and many have been patented for practically solving the problem, most of them depending upon various arrangements and locations of bolts or rivets. These latter, however, are sub-

ject to two serious objections, viz., they weaken the wood by cutting it across the grain at various vital points, and they mutilate the exterior surface, which should be whole and smooth in order not to deface the shoe lining and interfere with the proper manufacture of the shoes.

Accordingly my present invention aims to provide a further improvement in this line, which secures the desired strength and bracing effect without materially weakening the wood or mutilating the smooth external surface of the heelpart where it comes in contact with the shoe lining.

In carrying out my invention I employ a substantially **A**-shaped member so located, between the front end of the heelpart and the thimble socket thereof, as to bind the wood at the most critical point, said member being embedded entirely within the last so that no part thereof can come in contact with the shoe lining, and having its parts flared at the proper angle for giving the greatest strength of resistance to the complex strains which the various operations above alluded to bring upon the heelpart of a hinged last in manufacturing a shoe.

In the following description, taken in connection with the accompanying drawings, I point out further constructional details and advantages of my invention with reference to the preferred embodiment thereof herein disclosed, and in the appended claims the invention is still further defined.

In the drawings, Figure 1 is a perspective view of a last containing my invention. Figs. 2 and 3 are sectional vertical views thereof taken on the line 3, Fig. 1, showing different binding means for the retaining member. Fig. 4 is a similar vertical sectional view on the same line, showing the last formed for receiving the retaining member.

I have shown my invention applied to that form of hinged last known in the market as the Krentler two piece last and found in Patent No. 608,006 of July 26, 1898 and No. 764,894 of July 12, 1904, comprising a forepart *a* and a heelpart *a*¹ connected by a vertical plate hinge *a*² pivotally mounted at *a*³ in the forepart and held by transverse bolts *a*⁴, *a*⁵ in the heelpart.

The heelpart is provided with a usual spindle socket *a*⁶ and thimble *a*⁷ therein.

Located between the front end of the heel-part and said spindle socket, I provide a retaining member *b* which, in its construction, location and arrangement with relation to other parts, constitutes my invention. I first bore opposite vertical holes *b*¹, *b*² through the last from top to bottom slightly divergent toward their lower ends, as clearly shown in Fig. 4, and connect their upper ends by a groove *b*³. Viewing the drawings, it will be seen that these holes are located at either side of the vertical hinge, whose position is indicated in dotted line, Fig. 4, and are preferably in a transverse plane at the rear of said hinge. Also these holes are placed obliquely, as shown in Fig. 4, at such an angle that they do not correspond with the natural line of cleavage of the wood and are not in the same vertical plane with any other holes or cuts, such as the spindle hole, hinge plate, and vertical rivet sometimes employed, but pass athwart these various cuts and parts. In the cavity *b*¹, *b*², *b*³, I drive a staple or light piece of very strong unyielding wire *b*⁵ in the shape of an inverted U and anchor the lower ends of the legs thereof permanently, either by riveting them to the usual heel-plate *b*⁶, as shown in Fig. 3, or to retaining washers or heads *b*⁷ beneath said heel plate, as shown in Fig. 2. The result is that the wire member *b* is retained in such a manner and position as to resist splitting and spreading tendencies in whatever direction they naturally come in connection with the various steps of shoe manufacture. The retaining member *b* is located at such a point that there is very little tendency for the heelpart to be crushed and hence said member distorted vertically at that point, and yet it is in the very position where it can protect to best advantage those parts which are liable to become crushed and split; and all this is accomplished without mutilating or cutting into the side walls of the heelpart in any way whatever. This is a point of great practical value and importance in certain departments of shoe manufacture.

Without undertaking to set forth all the advantages and embodiments of my invention (as I am aware that various changes in form, arrangement and location of parts may be resorted to without departing from my invention) what I claim as new and desire to secure by Letters Patent of the United States is:—

1. A last, having its heelpart provided with a vertical U-shaped binding member whose legs are entirely surrounded by the wood of the heel part and permanently secured at the bottom of the last. 60

2. A last, having its heelpart provided with a vertical U-shaped binding member whose legs are entirely surrounded by the wood of the heelpart, said legs at their lower ends having lateral enlargements for anchoring said member in unyielding position. 65

3. A last, having its heelpart provided with a vertical U-shaped binding member whose legs are entirely surrounded by the wood of the heelpart, and a heel plate, said legs being riveted permanently to said heel plate. 70

4. A last, comprising a forepart and heelpart, hinged together, the hinge part having its rear portion extending vertically into the front end of the heelpart, and an inverted U-shaped retaining member located between the spindle socket of the last and the front end of the heelpart, said retaining member having its legs extending vertically in and surrounded by the wood of the last at the opposite sides of, and out of vertical alinement with, the rear portion of said hinge part and permanently secured in said heelpart. 75

5. A divided last, whose parts are connected by a vertical union, combined with an inverted U-shaped retaining member embedded in the heelpart and having its legs extending divergently downward and entirely surrounded by the wood of the heelpart adjacent the opposite sides of the latter, and means for permanently retaining said member in position. 85

6. A divided last, comprising a forepart and heelpart, a vertical hinge connecting the same, and binding means extending vertically in the heelpart of said last at the opposite sides of said hinge. 95

7. A last, having its heelpart provided with a vertical U-shaped binding member and means for binding together the free ends of the legs thereof. 100

In testimony whereof, I have signed my name to this specification, in the presence of two subscribing witnesses.

FREDERICK JOHN SHAINSEY, SR.
